M. M. GRUBER

LOCKING DEVICE

Filed Feb. 21, 1923

FIG. 1.

FIG. 2.

FIG. 3.

FIG. 4.

Morris M. Gruber Inventor
By his Attorney
Schechter Hatch

UNITED STATES PATENT OFFICE.

MORRIS M. GRUBER, OF EAST ORANGE, NEW JERSEY, ASSIGNOR, BY MESNE ASSIGNMENTS, TO SONORA PHONOGRAPH COMPANY, INC., A CORPORATION OF NEW YORK.

LOCKING DEVICE.

Application filed February 21, 1923. Serial No. 620,470.

My invention relates generally to a simplified locking device for holding an article or series of articles in position upon a support.

5 A further object of the invention is to provide a contact member and locking means adapted and for use on the usual turn-table spindle of a phonograph.

More particularly, this invention has for 10 its object the provision of means whereby one or a plurality of phonograph records may be supported upon the turn-table and locked in position thereon to permit easy 15 shipment or carrying. The invention is particularly applicable to portable phonographs, which are mounted in carrying cases, 20 permitting of a substantial number of records being placed upon the turn-table and carried within the case provided they are locked firmly in position.

It is an object of this invention to provide the usual phonograph spindle with an extension so that a large number of records or similar articles may be mounted thereon.

25 It is a further object of this invention to provide a member which is slidable upon said extension of the usual phonograph spindle, so that it may contact with the uppermost record and then be locked in position 30 on said spindle, to prevent axial movement of said records. The records will be mounted, of course, on the spindle extension and thus held against lateral movement.

35 It is a further object of this invention to provide a contact member and locking means therefor, as set forth in the preceding paragraph, which can be readily unlocked and dismounted without the use of tools or apparatus of any kind.

40 With these and other objects in view, to be more fully set forth hereinafter, the invention consists in the novel construction, combination of elements, and arrangement of parts which will be exemplified in the 45 operation and construction hereinafter described in the following specification and illustrated in the accompanying drawings, considered together or separately.

The inventive idea involved is capable of receiving a variety of mechanical expressions, some of which, for the purposes of illustration, are shown in the accompanying drawings.

The invention will first be described in connection with the accompanying drawings, 55 illustrating one embodiment of the invention, wherein similar reference characters are used to designate corresponding parts throughout the several views, and then more specifically defined and indicated in the appended claims.

While the invention will be described in connection with locking phonograph records upon a turn-table, it will be obvious as the description proceeds, that any article or a 60 plurality of articles of any other description, 65 may be locked upon a supporting platform in similar manner by the use of the same device.

In the accompanying drawings, 70

Fig. 1 is a plan view of a portable phonograph showing the cover in open position and having my invention applied thereto.

Fig. 2 is a side view with parts broken away of the device shown in Fig. 1. 75

Fig. 3 is a plan view of the device embodying my invention.

Fig. 4 is a vertical disassembled view of the spindle extension and the contact member and locking means mounted thereon. 80

Referring to the drawings, there is shown a portable phonograph comprising a case 10 having a hinged front 11, adapted to be let down when the phonograph is in use to expose the amplifier, and having a cover 12 85 which, when lifted, exposes the turn-table and tone arm. The phonograph is operated by a spring motor (not shown) within the casing, said motor being wound by the usual handle 13 extending outside of the casing. 90 Within the case 10 is shown a motorboard 15 through which extends a spindle 16 upon which is mounted a turn-table 17 adapted to carry the record to be played. The usual tone arm 20 is pivoted in one corner of the 95 case as at 21 and is provided with the usual

reproducer 22 and stylus 23. When the tone arm is in ineffective position, it is at one side of the case 10 substantially clear of and above the turn-table 17, so that a plurality of records may be piled upon the turn-table without interfering with the closing of cover 12, when the device is to be carried.

The plurality of records to be carried may be mounted on an extension of spindle 16, 10 said extension being in the form of a rod 25 similar to said spindle 16 and provided at its lower end with a threaded stem 26 adapted to fit into a threaded bore 27 in the upper end of the spindle 16 to lock said extension 15 firmly to said spindle.

It is apparent that unless the records were held against movement axially of said spindle and its extension, they would fall off and probably be broken within the carrying case, as well as probably injure the reproducer and the tone arm. To lock the records upon the spindle, I provide a contact member 30 in the form of a plate which may be of any desired and suitable diameter, 25 preferably corrugated, as shown at 31, and giving a maximum of strength to the plate which is preferably made of thin metal. The plate 30 is slid down the spindle extension until it contacts with the uppermost 30 record. Means are now provided for locking the contact plate against axial movement until it is desired to release the records. For this purpose, there are provided leaf springs 35, 36 fixed at their outer ends to the under- 35 side of the contact plate as at 37 and having their free ends in engagement with the spindle extension 25. A collar having a spindle knob 39 at its upper end extends centrally through the plate and is slidable 40 upon said spindle extension 25. Said collar 38 is provided with slits through which extend the free inner ends of leaf springs 35, 36, so that said collar in effect carries said inner ends which are slidable in and out of 45 said slots. The springs are of such length that they incline slightly upwardly toward the spindle extension 25, so that they bear downwardly on said spindle surface and grip the spindle between their inner ends. 50 To break the frictional engagement between said springs and the spindle, the knob 39 and collar 38 are pulled upwardly to raise the inner ends of leaf springs 35 and 36 out of engagement with said spindle, so that the 55 sleeve and its attached contact plate may be slid freely along the spindle extension 25. In this manner, it may be slid completely off the spindle extension to permit removal of the records or it may be slid to any other 60 position on said spindle extension, and by releasing knob 39 the leaf springs 35 and 36 are again moved downwardly into frictional engagement with the spindle extension 25. It is thus apparent that the knob 65 may be moved by the fingers of one hand,

certain of the fingers pressing against the plate while the other fingers pull upon the knob.

In accordance with the provisions of the patent statute, I have described the principle of my invention together with the apparatus which I now consider to represent the best embodiment thereof, but I desire it understood that my invention is not confined to the particular form of apparatus 70 herein shown and described, the same being merely illustrative, and that the invention can be carried out in other ways without departing from the spirit of my invention, and, therefore, I claim broadly the right to 75 employ all equivalent instrumentalities coming within the scope of the appended claims, and by means of which the objects of my invention are attained, and the new results 80 accomplished, as herein set forth, as it is 85 obvious that the particular embodiments herein shown and described are only some of many that can be employed to attain these objects and accomplish these results.

Having now described my invention, what 90 I claim and desire to secure by Letters Patent, is:—

1. In a device of the character described, a record support, a spindle projecting beyond said support and adapted to transfix 95 disk phonograph records by their central orifices, a record securing plate slidable along said spindle, a plurality of spring shoes engaging said spindle at their inner ends and secured at their outer ends to said 100 disk, and means to flex said spring shoes to draw their inner ends out of contact with said spindle.

2. In a device of the character described, a record support, a spindle projecting beyond said support and adapted to transfix 105 disk phonograph records by their central orifices, a record securing plate provided with a central collar slidable upon the surface of said spindle, a pair of leaf springs 110 secured at their outer ends to said plate, and passing through slits in said collar to engage said spindle with their inner ends, said collar having a sliding movement relative to 115 said plate, whereby movement of the collar relative to the plate may flex said springs to move them out of engagement with said spindle.

3. In a device of the character described, a record support, a spindle projecting beyond said support and adapted to transfix 120 disk records by their central orifices, a collar slidable upon said spindle, said collar being provided with radially arranged, inwardly projecting, upwardly slanting slits extending through the wall of said collar, spring members each having its inner end positioned in one of said slits and its outer end extending radially from said collar and secured at its extremity to a record securing 125 130

plate arranged concentrically to said collar and having a central orifice in which said collar is positioned, whereby said collar and said plate may be moved together along said spindle and when said collar is moved along said spindle and relatively to said plate, the ends of said spring members positioned in the slits of said collar will be pressed against said spindle by a movement in one direction

of said collar and drawn out of contact with said spindle by the reverse movement of said collar, thus permitting said plate to be locked to said spindle by relative movement of said collar to said plate.

This specification signed this 9th day of ¹⁵ February, 1923.

MORRIS M. GRUBER.
